(57) **CLAIM**

The ornamental design for a bottle as shown and described.

DESCRIPTION

FIG. 1 is a perspective view of a bottle showing my new design;

FIG. 2 is a front elevational view thereof;

FIG. 3 is a rear elevational view thereof;

FIG. 4 is a right-side elevational view thereof;

FIG. 5 is a left side elevational view thereof;

FIG. 6 is a top plan view thereof;

FIG. 7 is a bottom plan view thereof;

FIG. 8 is another perspective view thereof; and,

FIG. 9 is an enlarged view, taken from within portion 9 of FIG. 8.

The evenly dashed broken lines shown in the drawings illustrate parts of the article as well as the designation of enlargement views which form no part of the claimed design. The dash-dot broken lines shown represent boundaries of the claim, forming no part thereof.
